UNITED STATES PATENT OFFICE.

JOSIAH LETCHWORTH, OF BUFFALO, NEW YORK.

SNAP-HOOK.

SPECIFICATION forming part of Letters Patent No. 380,124, dated March 27, 1888.

Application filed May 18, 1887. Serial No. 238,596. (No model.)

To all whom it may concern:

Be it known that I, JOSIAH LETCHWORTH, of the city of Buffalo, in the county of Erie and State of New York, have invented a new 5 and useful Improvement in Snap-Hooks, of which the following is a specification.

This invention relates to that class of snap-hooks in which the hook is provided with a flat steel spring which closes the mouth of the 10 hook. A snap-hook of this kind requires a strong spring for holding the mouth of the hook closed, and the edges of the spring, being square and sharp, frequently injure the thumb or finger on bearing down on the spring to release 15 the hook.

The object of my invention is to remedy this difficulty; and my invention consists in providing the spring with a bearing-piece for the thumb or finger, whereby the spring can be 20 more conveniently handled, as will be herein-after described, and pointed out in the claim.

In the accompanying drawings, Figure 1 is a side elevation of a snap-hook provided with my improvement. Fig. 2 is a top plan view 25 thereof. Fig. 3 is a cross-section in line $x x$, Fig. 2. Fig. 4 is a fragmentary bottom plan view of the spring and bearing-piece secured thereto. Fig. 5 is a side elevation of the bearing-piece.

30 Like letters of reference refer to like parts in the several figures.

A represents the body of the hook, formed at one end with a curved portion, b, and at its opposite end with a loop, C, adapted to receive 35 the end of a strap.

D represents the flat spring, secured to the body A near the loop C and engaging with its opposite end against the under side of the end of the hook, so as to close the mouth thereof.

E represents the bearing or thumb piece secured to the outside or top of the spring. This thumb-piece is preferably of oval shape, as shown in the drawings, and its top or face is made slightly rounding to present a smooth surface to the thumb or finger. The thumb-piece E preferably projects beyond the edges of the spring and is secured to the latter by lugs or ears e e, formed on the sides of the thumb-piece and bent or clinched against the under side of the spring, as shown in Figs. 3 45 and 4, but may be secured in any other suitable manner. The thumb-piece E is preferably cast of malleable iron, with the ears or lugs e e arranged at right angles to the bearing-piece, as shown in full lines in Fig. 5, and 50 the ears or lugs e e are readily closed against the under side of the spring by a cold-shut. The thumb-piece E forms a convenient and safe guard for the thumb or finger while bearing down on the spring to release the hook. It can 55 be constructed at very little expense, and can be readily attached to snap-hooks already in use.

I claim as my invention—

The combination, with the hook and the flat 65 spring which closes the mouth of the hook, of an independent thumb-piece, E, applied to the outer side of the spring and provided with lateral ears e e, which are closed against the under side of the spring, substantially as set forth. 70

Witness my hand this 22d day of April, 1887.

JOSIAH LETCHWORTH.
